UNITED STATES PATENT OFFICE.

THOMAS C. JOHNSON, OF NEW HAVEN, CONNECTICUT, ASSIGNOR TO WINCHESTER
REPEATING ARMS CO., OF NEW HAVEN, CONNECTICUT, A CORPORATION.

MILITARY SHOULDER-ARM.

1,172,714.

Specification of Letters Patent. Patented Feb. 22, 1916.

Application filed December 6, 1915. Serial No. 65,239.

To all whom it may concern:

Be it known that I, THOMAS C. JOHNSON, a citizen of the United States, residing at New Haven, in the county of New Haven and State of Connecticut, have invented a new and useful Improvement in Military Shoulder-Arms; and I do hereby declare the following, when taken in connection with the accompanying drawings and the characters of reference marked thereon, to be a full, clear, and exact description of the same, and which said drawings constitute part of this application, and represent, in—

Figure 1 a view partly in right hand side elevation, and partly in vertical section of the middle portion of a military shoulder-arm constructed in accordance with my invention. Fig. 2 a broken reverse plan view thereof. Fig. 3 a detached broken plan view 20 of the rear end of the forestock. Fig. 4 a detached plan view of the forestock-tie-plate. Fig. 5 a detached view in front elevation of the receiver-extension. Fig. 6 a detached view in rear elevation of the fore-25 stock.

My invention relates to an improvement in military shoulder-arms, the object being to provide simple and reliable means for holding the forestock against forward displacement without imposing any strain upon the barrel, and with the minimum cutting of the forestock itself.

With these ends in view, my invention consists in a military shoulder-arm having certain details of construction as will be hereinafter described and pointed out in the claims.

In carrying out my invention as herein shown, I employ a forestock tie-plate 2 having flat upper and lower faces and located in a central, longitudinal clearance groove or slot 3 having a flat bottom wall and formed in the upper face of the rear end of the forestock 4, the forward end of the said plate being rounded as at 5 and formed with a vertical, threaded hole 6 for the reception of a vertically arranged retaining-screw 7 extending upward through a bushing or escutcheon 8 inserted into a vertical shoul-50 dered bore 9 formed in the forestock in line with the hole 6 in the plate 2 and intersecting the forward end of the said slot or

groove 3. By employing a tie-plate with a flat lower face instead of with a depending locking-lug as heretofore proposed, I avoid 55 cutting the forestock to receive the said lug the locking effect of which is in my present construction taken by the screw 7, which may be of any required size to discharge this function.

At its rear end the tie-plate 2 is formed with a threaded shank 10 entering a threaded opening 11 in a lug 12 projecting from the forward face of a receiver-extension 13 screwed upon the receiver 14 which is furnished with a threaded opening 15 for receiving the shank 16 of the gun-barrel 18. At its rear end, the forestock 4 is formed with a short tenon 17 entering a shallow recess 23 in the forward face of the receiver-extension 13 the rear face of which is formed with a threaded lug 19 for the reception of a screw 20 passing upward into it through the forward tang 21 of the box-magazine 22. If desired, the plate 2 might be formed integral with the receiver-extension, though the construction shown is preferred. So far as my present invention is concerned, the receiver-extension might be made integral with the receiver. The term "receiver" in 80 the claims is to be understood as covering the receiver whether its extension is integral or otherwise, except in those claims in which the receiver-extension is specifically mentioned.

I claim:

1. In a military shoulder-arm, the combination with the receiver thereof, of a forestock, a tie-plate extending forward from the receiver, connected therewith and having a flat lower face, and a vertically arranged screw passing upward through the forestock and into the said tie-plate.

2. In a military shoulder-arm, the combination with the receiver and receiver-extension thereof, of a forestock formed in the upper face of its rear end with a groove, a forestock tie-plate located in the said groove, connected at its rear end with the receiver-extension and having a flat lower face, and a vertically arranged screw passing upward through the forestock into the said plate.

THOMAS C. JOHNSON.
